UNITED STATES PATENT OFFICE.

THOMAS YAPP, OF CLEVELAND, OHIO.

CAN.

SPECIFICATION forming part of Letters Patent No. 317,957, dated May 12, 1885.

Application filed May 1, 1884. (No model.)

To all whom it may concern:

Be it known that I, THOMAS YAPP, a citizen of the United States, residing at Cleveland, county of Cuyahoga, and State of Ohio, have 5 invented certain new and useful Improvements in Cans; and I do hereby declare the following to be a description of the same, and of the manner of constructing and using the invention, in such full, clear, and concise and exact terms as to enable any person skilled in the art to which it appertains to construct and use the same, reference being had to the accompanying drawing, forming a part of the specification, the principle of the invention 15 being herein explained and the best mode in which I have contemplated applying that principle, so as to distinguish it from other inventions.

My invention relates to the sealing up of 20 the mouths of cans made of tin or other metal, and which are used for the storage of oils or other substances. Said invention is a screw device, by which the inconvenience and expense and in some circumstances the danger 25 of a soldering process are obviated.

The drawing is a vertical sectional view of the cap as applied to the can-cover.

The cap consists of two parts, A and B, the latter fitting over the former and the two 30 screwed together, as I proceed to describe.

Part A is a metallic disk or plate so pressed as to be provided with the annular projecting flange *d*, which said flange is impressed on its exterior surface with a male screw. Said 35 part A is cut out on its top to form the opening *c*, which opening may be larger or smaller, as is desired, and as the limits of the said top may permit. The lateral flange *a* is of sufficient extent to lap upon a portion of the 40 cover C of the can, which it does continuously around the mouth of the can. Said part is soldered at its flange *a* to the under side of the can-cover before said cover is attached to the other portions of the can, the flange *d* projecting outwardly through the mouth of the 45 can provided in said cover.

Part B is an unperforated metallic disk or plate so pressed as to be provided with the projecting annular flange *e*, said flange impressed on its interior surface with a female 50

screw, said screw fitting closely over the male screw impressed on flange *d*. Said part has the annular lateral flange *b*, of sufficient extent to lap upon portions of the cover C and continuously around the mouth of the can. 55

When part B is applied to part A and screwed home upon it by means of the reciprocating screw devices mentioned, flange *b* is brought down tightly upon portions of the cover C about the can's mouth, and so forms, 60 in connection with the flange *a*, a clamping device to clamp between said flanges said portions of the can-cover.

In practice the can is filled through opening *c*, and then part B is screwed over A. I 65 may also use a gasket, soaked in melted rubber, between flange *b* and the cover C. Also I am not confined to the annular shape of the flanges *a* and *b*, but they may be in other shapes. For the emptying of the can, part 70 B is simply unscrewed from A, and the can's mouth is open. Thus my device saves the can from mutilation and permits it to be filled and sealed repeatedly, which makes a great saving in cans. 75

I therefore claim—

1. In a can-sealing device, a cap consisting of two separate parts, A and B, one of said parts—viz., A—being perforated, and the other of said parts—viz., B—being unperforated, the 80 unperforated part covering the perforated part, said two parts connected together by a screw device impressed upon their respective surfaces, said parts having lateral matching flanges *a* and *b* that lap together, said flanges 85 being thus adapted to clamp between them portions of the can-cover that lie about the mouth of the can, substantially as set forth.

2. In a can-sealing device, the combination, with a can-cover, of a cap consisting of two 90 parts, A and B, said parts fastened together by a screw device impressed upon their respective surfaces, said two parts having lateral matching flanges *a* and *b*, one of said flanges—viz., *a*—lapping upon the inner surface of 95 the can-cover continuously about the mouth of the can, and the other of said flanges—viz., *b*—lapping upon the outer surface of the can-cover continuously about the mouth of the can, all for the purpose of clamping between 100

said flanges said portions of the can-cover, and for the purpose of making a tight joint, substantially as set forth.

3. In a can-sealing device, the combination, with portions of the can-cover contiguous to the mouth of the can, of the two parts A and B, said parts having the base flanges *a* and *b*, said flanges clamping between them the portions of the can-cover, C, aforesaid, 10 said part A being perforated and having the flange *d*, projecting outwardly through the mouth of the can, said flange impressed with a male screw on its exterior surface, part

B being unperforated and impressed on the interior surface of its flange *e* with a female 15 screw, said parts screwed to each other by means of said screw device, and for the purposes substantially set forth and described.

In testimony that I claim the foregoing to be my invention I have hereunto set my hand 20 this 31st day of March, A. D. 1884.

THOMAS YAPP.
